PACKAGING TRAY

William P. Jacobson, Rockford, Ill., assignor to Anderson Bros. Mfg. Co., Rockford, Ill.

Filed Jan. 4, 1971, Ser. No. 103,947

Term of patent 14 years

Int. Cl. D9—03

U.S. Cl. D9—180

FIG. 1 is a front perspective view of a packaging tray showing my new design;

FIG. 2 is a top plan view thereof;

FIG. 3 is a rear elevation thereof;

FIG. 4 is an elevation of the end opposite that shown in FIG. 1; and

FIG. 5 is a bottom plan view thereof.

I claim:

The ornamental design for a packaging tray, substantially as shown.
